HOLDER FOR A DISPOSABLE BOTTLE

Stanley M. Hoffstein, Wilmington, Del.

Application April 8, 1959, Serial No. 55,412

Term of patent 14 years

(Cl. D83—8)

FIG. 1.

FIG. 2.

FIG.3.

FIG.5.

FIG.4.

The dominant features of my design reside in the full line portions of the drawings.

I claim:

The ornamental design for a holder for a disposable bottle, substantially as shown and described.
